CLAIM

I claim a new ornamental design for a wheel, as shown and described.

DESCRIPTION

FIG. 1 is a perspective view of a wheel according to a preferred embodiment of my new design;

FIG. 2 is a front elevational view of the wheel of FIG. 1;

FIG. 3 is a left side elevational view of the wheel of FIG. 1, the right side elevational view of the wheel of FIG. 1 being a mirror image of FIG. 3;

FIG. 4 is a top plan view of the wheel of FIG. 1;

FIG. 5 is a bottom plan view of the wheel of FIG. 1;

FIG. 6 is a rear elevational view of the wheel of FIG. 1;

FIG. 7 is a perspective view of a wheel according to a second embodiment of my new design; and,

FIG. 8 is a front elevational view of the wheel of FIG. 7.

The broken lines shown in the drawings represent unclaimed portions of the wheel, and form no part of the claimed design.
